(57) **CLAIM**

The ornamental design for a wireless microphone charging case, as shown and described.

DESCRIPTION

FIG. 1 is a perspective view showing a first embodiment of my new design for a wireless microphone charging case; FIG. 2 is another perspective view of the design of FIG. 1; FIG. 3 is a front view of the design of FIG. 1; FIG. 4 is a rear view of the design of FIG. 1; FIG. 5 is a left side view of the design of FIG. 1; FIG. 6 is a right side view of the design of FIG. 1; FIG. 7 is a top view of the design of FIG. 1; FIG. 8 is a bottom view of the design of FIG. 1; FIG. 9 is an enlarged view of a portion indicated in FIG. 6; FIG. 10 is an enlarged view of a portion indicated in FIG. 8; FIG. 11 is a perspective view showing a second embodiment of my new design for a wireless microphone charging case; FIG. 12 is another perspective view of the design of FIG. 11; FIG. 13 is a front view of the design of FIG. 11; FIG. 14 is a rear view of the design of FIG. 11; FIG. 15 is a left side view of the design of FIG. 11; FIG. 16 is a right side view of the design of FIG. 11; FIG. 17 is a top view of the design of FIG. 11; FIG. 18 is a bottom view of the design of FIG. 11; FIG. 19 is an enlarged view of a portion indicated in FIG. 16; FIG. 20 is an enlarged view of a portion indicated in FIG. 18; FIG. 21 is a perspective view showing a third embodiment of my new design for a wireless microphone charging case; FIG. 22 is another perspective view of the design of FIG. 21; FIG. 23 is a front view of the design of FIG. 21; FIG. 24 is a rear view of the design of FIG. 21; FIG. 25 is a left side view of the design of FIG. 21; FIG. 26 is a right side view of the design of FIG. 21; FIG. 27 is a top view of the design of FIG. 21; FIG. 28 is a bottom view of the design of FIG. 21; FIG. 29 is an enlarged view of a portion indicated in FIG. 26; and,

(Continued)

FIG. 30 is an enlarged view of a portion indicated in of FIG. 28.

The broken lines are included to show features that form no part of the claimed design.
